F. C. HUNT

HEATING RADIATOR

Filed Oct. 23, 1922

FIG. 1.

FIG. 3.

FIG. 4.

FIG. 2.

INVENTOR
FRED C. HUNT
By *Jefferson Haught & Co*
ATTYS.

UNITED STATES PATENT OFFICE.

FREDERICK CHARLES HUNT, OF LONDON, ONTARIO, CANADA.

HEATING RADIATOR.

Application filed October 23, 1922. Serial No. 596,499.

To all whom it may concern:

Be it known that I, FREDERICK CHARLES HUNT, a subject of the King of Great Britain, and a resident of the city of London, in the county of Middlesex, in the Province of Ontario, Canada, have invented certain new and useful Improvements in Heating Radiators, of which the following is the specification.

10 My invention relates to improvements in heating radiators and the object of the invention is to devise a radiator for use in hot water or steam heating systems in which each section is constructed of an integral drawn tube of metal formed to shape.

15 A further object is to devise improved means whereby the sections are connected together at top and bottom, making a steam or water tight joint without the use of gas-
20 kets.

25 A still further object is to devise a radiator which will effect a considerable saving in fuel consumption by increasing the radiation thereof, and another object is to devise a radiator which will be comparatively light in weight and will only require a small quantity of hot water or steam with a correspondingly small piping system.

30 My invention consists of a radiator constructed and arranged all as hereinafter more particularly described and illustrated in the accompanying drawing in which:

35 Fig. 1 represents an elevational view of a radiator constructed according to my invention illustrating the same partly in section to show the connections at the top and bottom of each section.

Fig. 2 is a side view thereof.

40 Fig. 3 is a horizontal section through the line 3—3 Figure 1, and

45 Fig. 4 is an enlarged vertical sectional view through the upper portion of the radiator taken through the line 4—4 Figure 2.

Like characters of reference indicate cor-
50 responding parts in the different views.

1 are the sections of the radiator constructed of a drawn metal tube such as aluminum formed to shape, their ends 2 being bent in towards each other and suitably welded together. 3 are caps of inverted U-shaped cross section adapted to extend over the upper and lower ends of each section in order to give a finished appearance. 4 is a vertical web inserted into each section

for giving strength and rigidity thereto. 5 55 are nipples, each having the enlarged annular central portion 6 and the threaded ends 7 and 8. The enlarged annular portion of each nipple is provided with radially disposed orifices 9 extending outwardly from 60 the interior thereof to the exterior.

The nipples 5 are inserted into the radiator sections 1 so that the enlarged annular portion 6 is disposed internally thereof with the threaded ends 7 and 8 protruding laterally through the orifices 10 and 11, it being understood that a nipple is provided in the vicinity of each end of each section.

12 are interiorly threaded flanged collars adapted to be screwed onto the ends 7 and 8 respectively of adjacent nipples as is clearly illustrated in Figures 1 and 4 of the drawing in order to connect the respective sections 1 together. 13 and 14 are respectively the water or steam inlet and outlet 75 return pipes, the pipe 13 provided with the usual valve 15.

16 are legs provided with socket-like upper ends 17 adapted to receive the lower ends of the end sections, said legs resting 80 on the floor of the room.

A radiator constructed according to my invention will be exceedingly easy to assemble and moreover can be varied in size to suit the different requirements. If constructed of aluminum it will be very light in weight and moreover, by the use of nipples and collars, water or steam tight joints between the sections can be readily made without the use of gaskets or packing. 90

What I claim as my invention is:

1. A radiator comprising a plurality of drawn metal tube sections formed to shape and their ends pinched in towards each other and welded together, each radiator section being provided with registering orifices in its side walls in the vicinity of the top and bottom thereof, nipples inserted into each section with their opposed threaded ends protruding through the adjacent orifices, and collars threaded onto the adjacent ends of adjacent nipples for holding the sections in spaced relation to each other. 100

2. A radiator comprising a plurality of drawn metal tube sections formed to shape 105 and their ends pinched in towards each other and welded together, each radiator section being provided with registering orifices in its

2
side walls in the vicinity of the top and bottom thereof, nipples having enlarged central portions with orifices extending from the interior to the exterior thereof, said nipples having opposed threaded ends, the enlarged portion of each nipple being disposed interiorly of the radiator section with the opposed ends protruding through the orifice in the side walls thereof, and internally thread-

ed collars screwed onto adjacent ends of adjacent nipples for holding the sections in spaced relation to each other. ¹⁰

London, Ontario, October eleventh, 1922.

FREDERICK CHARLES HUNT.

Signed in the presence of:

M. MACPHERSON,
MARY CAMPBELL.
